UNITED STATES PATENT OFFICE.

HAROLD W. SHONNARD, OF MONTCLAIR, NEW JERSEY, ASSIGNEE TO ELEVATOR SUPPLIES COMPANY INC., OF HOBOKEN, NEW JERSEY, A CORPORATION OF NEW JERSEY.

ELEVATOR-DOOR OPERATION.

Application filed May 19, 1925. Serial No. 31,302.

The present invention relates to elevator door operation and more particularly to a system and mechanism by means of which an elevator door and car gate may be simultaneously operated either automatically or by hand control.

In my co-pending application, Serial No. 729,855 I have described an apparatus by means of which an elevator door or car gate may be operated, the operation being controlled by either electrical or mechanical means. The apparatus and system herein-after described embodies various elements and mechanisms shown and described in my co-pending application but which are not claimed herein. The present invention relates to a new embodiment of the units or elements shown in my co-pending application in a novel system, by means of which the elevator operating units are greatly improved and by means of which the installation of the elevator units is greatly simplified, resulting in reducing the cost of installation and operation thereof.

The primary object of the present invention is to provide a new and improved means for the automatic operation of elevator doors and car gates.

Another object of the invention is to provide a new method for the mounting of the units or system of units in the elevator shaft, whereby the installation may be put into operation with greater ease and in a comparatively short time, and whereby the system may be installed with greater accuracy in general than has heretofore been possible.

A further object of the invention is to provide an improved form of apparatus for the automatic operation of car gates and elevator doors which is adapted to be used on any form of elevator, in other words, which is of a form such as to be of universal application to elevators.

With these and other objects in view the invention comprises various features and combinations hereinafter described and particularly defined in the claims.

In the installation of units for the operation of elevator doors it has heretofore been the practice to design door operating mechanisms to meet the particular conditions or form of installation to which they are to be applied, and thereafter to have the units

installed by experts following out the details of the layout, and installing the unit in whatever manner appears to be best under the circumstances or conditions to be met. Following this procedure has resulted in much loss of time and inefficiency in installation, and frequently also in the use of make-shift apparatus to meet the various peculiarities or conditions of installation, where the space for the usual form of apparatus has been insufficient.

By the means hereinafter described the difficulties inherent in the systems heretofore employed have been overcome, in that the devices are embodied in a form which may be employed in connection with any elevator installation or elevator system. Furthermore the units may be installed by any mechanic of average skill; in other words, the installation does not require the work of skilled men or experts, as have heretofore been required in connection with each special installation.

In the modern elevator shaft extending frequently up to about forty stories there is more or less variation in the shaft between the various floors, and the top of the shaft is very frequently out of alignment as much as four inches. In the installation of apparatus on the walls of the shaft it has been the practice heretofore to practically survey the whole shaft and to calculate out in advance the positions of various door operating valve units and thereafter to install the units in these positions with the necessary changes in the form of mounting to compensate for the local variations, and then to test out each separate unit in place and to make the necessary adjustments. This method of installation is very tedious and requires a great deal of time to install and to test out the units. By the means which I have devised the various units may be easily handled and may be installed in a small fraction of the time generally required for the operation.

The various features of my invention are illustrated in the accompanying drawings showing the preferred embodiment of my invention, in which

Fig. 1 is a part sectional view in perspective of an elevator car at a landing in the shaft, showing the shaft door and car gate in closed position and illustrating the pre-

ferred mode of mounting the various operating units in relation to the elevator car and the doors to be operated;

Fig. 2 is a horizontal sectional view of the elevator shaft and car illustrated in Fig. 1, the section being taken above the floor of the elevator car and indicating by dash lines the relative positions of various units which would not otherwise appear in this view;

Fig. 3 is a detailed vertical sectional view taken on the line 3—3 of Figure 2;

Fig. 4 is a detailed sectional view taken on the line 4—4 of Figure 3;

Fig. 5 is a vertical view taken on the line 5—5 of Figure 4;

Fig. 6 is a profile view of the apparatus shown in Figure 3 as seen from the left in this figure;

Fig. 7 is a detailed sectional view taken on the line 7—7 of Figure 3;

Fig. 8 is a plan view of the apparatus shown in Figure 6 showing the counterweight guide rail in section, and the preferred mode of attaching a door operating valve unit thereto;

Fig. 9 is a detailed view in elevation showing a section of the counterweight guide rail shown in Figure 8, and the bracket for mounting a valve unit thereon;

Fig. 10 is a horizontal sectional view taken on the section 10—10 of Figure 3;

Fig. 11 is a plan view of a mechanism similar to that shown in Figure 8, illustrating the manner in which the valve unit may be mounted on the car guide rail in place of on the counterweight rail in the shaft;

Fig. 12 is a vertical sectional view of the parts shown in Figure 11; and

Fig. 13 is a front view in elevation of the form of bracket shown in Figures 11 and 12 for connecting the valve unit to the car guide rail, the bracket being shown mounted on the guide rail.

The present invention comprises means whereby the elevator shaft door or shaft doors at any landing, together with the elevator car gate may be operated substantially simultaneously when the elevator car has arrived at the landing or when the car has been stopped within a predetermined distance thereof. The invention comprises also means whereby the shaft door or doors and car gate may be automatically operated by means of a switch or by means of mechanical hand control. The device also comprises means whereby the car gate may be opened between floors in the shaft when the elevator car is stopped, but the means provided for opening and closing the shaft door or doors prevents the operation of these doors except when the car is at the landing, or within a few inches of the landing as determined by the set or position of the door operator control valve unit.

Referring more particularly to Figure 1

of the drawings an elevator car 10 is shown at a floor landing 12 in an elevator shaft 14, the shaft doors 16, at the landing, being shown in closed position, as is also the car gate or car door 18, which is shown in part section with a portion of the car removed so as to clearly show the door operating mechanisms. Mounted in the elevator shaft 14 are the usual elevator guide rails 20, 22 and counterweight guide rails 24, 26, the former employed to guide the elevator during its ascent and descent through the elevator shaft, and the latter being employed for guiding the car counterweight to prevent swinging or interference with the elevator car in its movements in the shaft.

Connected to the elevator shaft door or doors are the usual toggle levers 28 having a handle 30, by means of which the doors may be opened and closed manually if desired. In order to operate the shaft doors by power, which will ordinarily be employed in connection with the apparatus, a pressure operated motor 32 of any desired form is mounted in any suitable position, preferably on a wall of the hatchway in proximity to the rear end of the elevator door. Pressure fluid, such as compressed air, is conducted to the engine or motor 32 through a pipe 34, the passage of fluid to the operating device 32 being controlled by means of a controller valve unit 36, the operation of which will be hereinafter described.

A valve unit 36 is positioned at each floor or landing in the shaft, and may be located in any suitable position therein, although I preferably mount the unit on one of the guide rails, either on one of the car guide rails, or one of the counterweight rails in the shaft, whereby the extreme difficulties encountered in the usual installation, due to variations in the wall of the shaft, are entirely overcome, and whereby the unit may be installed in a very small fraction of the time generally required for this purpose. At each landing or floor the valve unit 36 at the floor is connected to the corresponding elevator door operating engine 32, which opens and closes the shaft doors to which it is connected at the landing.

The valve 36 is connected to a fluid pressure supply line 38 by means of a pipe 214 through which the pressure fluid may be supplied to the unit; the valve is also connected to an exhaust pipe or exhaust line 40 by means of a pipe 212, through which exhaust air or pressure fluid is conducted away from the apparatus. The lines 38 and 40 are preferably run parallel through the elevator shaft in proximity to the guide rail on which the units are mounted, so that the pipes may be readily connected to the valve units 36, at the various landings.

A suitable tripping mechanism or operat-

ing mechanism for operating the valves 36 is connected to the elevator car in any suitable position so that the shaft door may be operated when the car is in a suitable position in proximity to the floor landing, and is so positioned with respect to the lever or part operated upon the valve unit 36 that the latter, and consequently the door operating engine controlled thereby, may only be operated when the car is stopped at any landing within a certain distance of the floor. Means are also provided so that the tripping mechanism may be put into tripping position only when the elevator car has come to a stop. At the same time that the shaft door is opened the elevator car gate 18 will also be opened as will be hereinafter more fully explained in connection with the description of the operation of the mechanism as a whole.

The elevator car door or gate 18 is connected through a toggle lever 42 of any suitable form to a pneumatic engine or door operating motor 44, which comprises a cylinder having a piston and cushioning means therein, the forward stroke of the engine, corresponding to the door opening movement, being attained by fluid pressure, and the return stroke being effected by a suitable spring in the cylinder. Any suitable form of motor 44 may be employed for the operation as is obtainable on the market, such, for example, as is described in Patent No. 1,540,972. The engine 44 is connected through a pressure fluid supply pipe 46 with a control valve 48, which I term an electro-pneumatic valve, which embodies a mechanism similar to the valve 36 and which is preferably positioned under the floor of the elevator car.

To the control valve 48 is connected, preferably in a manner so as to constitute a unitary structure, a fluid pressure operated motor or engine 50 (see Fig. 3), which is adapted to be operated substantially simultaneously with the motor 44, by means of a connection to the operating means. The engine 50 operates a tripping lever 52 which has mounted thereon a roller 54 adapted to contact with a valve-operating lever 56 connected to the control valve 36.

In order to operate the electro-pneumatic valve 48 and the engine 50, connected therewith, a supply line or flexible conducting pipe 58 is provided, which supplies compressed air or other pressure fluid, from an air compressor 59 or other source. The flexible pipe 58 is preferably attached under the elevator car by means of a suitable connection 60, as shown in Figure 2. An exhaust pipe 62 to which a muffler 64 may be attached (see Figure 2) is connected to the mechanism 48 for conducting away exhaust pressure fluid from the exhaust chamber of the mechanism.

In order to control the operation of the mechanism 48 an electric switch is preferably employed, which may be mounted in any suitable position so as to be under the control of the operator. The switch may be mounted in connection with the elevator controller 66 and is preferably mounted in the controller handle or in connection therewith so that the switch can only be closed to cause opening of the shaft doors when the handle 68 of the controller is in neutral position. For this purpose a push button may be positioned in the end of the controller handle 68 serving to make or break a circuit through circuit terminals when the controller is in neutral position. The details of construction of the switch mechanism does not form a part of the present invention and is not illustrated, therefore, in the drawings.

The electrical circuit through the terminals of the controlling switch is connected to operating solenoids around a plunger 70 (see Figure 10) which serves, through suitable operating mechanism, to operate the fluid pressure controlling valve in the mechanism 48. In order that the pressure fluid controlling valve in the mechanism 48 may be operated even in case of the failure of the electrical circuit, a mechanical connection to the plunger 70 is provided, which comprises a handle 72, connected by means of a system of levers, (as indicated in Figure 1) to a rod 74, which in turn is connected to the plunger 70.

The mode of operation of the mechanism 48 may now be described, with particular reference to Figure 10 and with reference also to Figures 3 and 6.

Assuming that the elevator car has been stopped within a certain distance, such as within three inches of the floor landing, by the operation of the controller, which will have been placed in neutral position, the valve operating switch, connected to the operating solenoid 76, (which, as above stated is preferably connected to the controller handle 68), is then closed, whereby a current is sent through the coils 76 of the solenoid, drawing the plunger 70 to the right in Figure 10, against the stop 78. By the movement of the plunger 70, the toggle arms 80, 82 are brought substantially into alignment, or are moved so that the heads 84, 86 are brought slightly beyond the center line 110 passing through the pivots 88, 90, whereby a spring 92, held at one end 91, is pressed downwardly against the top of a valve stem 94, which serves to force the valve 96 away from its seat 98, the lower face of the valve 96 being pressed against a ball 138 and holding it to its seat 142, whereby the passage 140 communicating with the pressure supply chamber 116 is closed off, and whereby the pressure in the chamber 100 and ports con-

nected therewith is released. A reduction in pressure takes place therefore in chamber 100 which is transmitted through passageways 102, 104 to the chamber 106 on one side of the piston 108, whereby the unbalanced pressure on the other side of the piston, in the portion of the chamber indicated by the numeral 110 forces the piston in a direction toward chamber 100, moving the valve disc 112 or closure 112 from its seat 114, thereby establishing communication between the chamber 116, connected to the pressure fluid supply line 58, and the inner chamber 118. By this movement of the piston 108 with its valve stem 120, the disk or closure 122 is brought against the seat 124, and communication between the chamber 126, leading to the exhaust pipe 62, and the chamber 118 is thereby cut off. The supply pressure from the pipe 58 is transmitted through chamber 118, through the passageway 128 through pipe 46 to the car gate operator or engine 44, located preferably on top of the car. The operator 44 is connected through suitable linkages to the operating lever 42 which serves to open the car gate as soon as the supply pressure reaches the operator. The car gate remains open through the action of the operator 44 until the plunger 70 is returned to its initial position whereby the piston 108 is actuated to cut off the fluid pressure and open the exhaust through the valve from the engine 44.

35 While the piston 108 is in the position for supplying pressure fluid to the operator 44, through the chamber 118 and pipe 46, the pressure fluid is also transmitted from chamber 118 through a pipe 130 to an engine or trip lever operator 132, which is preferably made of a part of or is directly connected with the operating unit 48. Through the operation of the engine 132 a trip lever 52 is operated which in turn moves a lever connected to the unit 36, causing operation thereof to transmit pressure fluid to the operating cylinder 32, operatively connected to the shaft doors 16.

50 When it is desired to close the car gate and the shaft doors, the appropriate switch in connection with the controller handle 68 is operated so as to pass a current through the coils of the solenoid 134 whereby the plunger 70 will be moved into the position (shown in Figure 10), in which the pressure by the toggle levers 80, 82 on the valve 96 and ball valve 138 is released. This movement of the plunger 70 may also be accomplished by mechanical means, such as by the hand lever 72 shown in Figure 1. In the position of the plunger, as shown in Figure 10, the toggle levers 80, 82 are out of alignment, and the piston 108 is in the position in which communication between the supply pressure pipe 58 and pipes 46 and

130, leading to the car gate operator 44 and trip lever operator or engine 132 respectively, is cut off. When the piston 108 is moved into the position shown in Figure 10, communication between the exhaust chamber 126 (leading to exhaust pipe 62) and the chamber 118, which is in direct communication with the pipes 46 and 130, is established, and exhaust takes place through these pipes to the exhaust chamber. 75

When the plunger 70 is moved into the position shown in Figure 10, in which position exhaust of pressure fluid takes place through the mechanism 48 and the doors are thereby closed, the movement of the plunger 80 is arrested by the stop 136, and the spring 92 is returned to its original position indicated in Figure 10. In this position the pressure of the spring 92 on the valve 96 is released, whereby the pressure contact on 85 the ball valve 138 is also released. At the time the pressure by the toggle levers on the valve 98 is released the pressure in the chamber 100, above the ball 138, is substantially 90 atmospheric, because of the communication of the chamber through the port 144 and opening 145 with the atmosphere, and the pressure in the passageway 140, which leads from the chamber 100 to the chamber 110, in communication with the pressure supply 95 pipe 58, is equal substantially to the supply pressure, whereby the unbalanced pressure behind the ball 138 in the passageway 140 forces it away from its seat. The movement of the ball forces the valve 96, in contact therewith toward its seat 98, and through the added impact or force of the fluid pressure from the pipe 140 against the lower face of the valve, the valve is forced to its seat, and is maintained in this position by the pressure in the chamber 100 which is immediately built up. 100

105 The trip lever operator or engine 132 comprises a cylinder 146 in which is a piston 148 which is connected to the trip lever 52 110 through a connecting rod 152 which is attached to the piston in the usual manner by a wrist pin connection 150. The connecting rod 152 may be attached to the trip lever 52 in any suitable way, as by means of a bolt 115 154, for example. The trip lever 52 is preferably mounted so as to swing or turn on a pivot 156, as shown more particularly in Figure 3, the lever 52 being supported from a bracket 158, which is preferably made integral with the casing surrounding the unit 48. In order to return the lever 52 to its inoperative position after the pressure of the fluid behind the piston 148 is released, a spring 160 may be mounted on a rod 162 between a stop member 164 and a nut or other holding means 166 at the end of the rod 162, the rod being connected to the lever 52 at any suitable point 168 and preferably mounted so as to slide in a bearing in the member 120 160. 125

164. When the rod 162 is retracted, the lever 52 will be turned about the pivot 156 until it is brought into its limiting position, as determined by a stop or lug 170 which 5 may be brought against an adjustable screw 172 or other equivalent means, preferably mounted on the bracket 158.

In order to prevent heating up of the solenoids 76 and 134 when the solenoid operating 10 current passes therethrough, I may employ a cut-out switch to break the circuit after the plunger 70 has been operated. For this purpose a rod 174, may be mounted so as to slide in a guide 176, and may be pivotally connected to the lever 52 by means of a screw bolt 15 or other connecting means 178. To the rod 174 is connected a lug or tripping member 180 which is adapted to operate in a slot 182 in a member 184, connected to which are 20 cut-out switches, which are in circuit with solenoids 76 and 134. The member 184 is pivoted on a pin 186, and when operated by means of the lug 180 on the rod 174 through the movement of lever 52, the circuit through 25 the operating solenoid is broken, thereby preventing heating up of the solenoid coils.

The flow of pressure fluid to the engine 30 takes place through the pipe 130 which is connected to the head end of the cylinder 146, as shown more particularly in Figure 5, the fluid passing through a port 186, which is preferably controlled by means of a regulating screw 188. The exhaust of pressure fluid from the cylinder 146 takes place on the 35 return stroke of the piston 148 in the cylinder, the pressure fluid being exhausted through the passageway 186 into the pipe 130 and also through a supplemental by-pass 190 in which a ball 192 is held to its seat by 40 means of a spring member 194, the tension of which may be regulated by a set screw 196, as will be apparent from Figure 4 of the drawings. During passage of pressure fluid to the cylinder through the port 186, 45 the ball valve 192 is held to its seat, but during exhaust of pressure fluid the ball will move away from its seat, thus permitting a quick exhaust of the pressure fluid.

In proximity to each landing in the 50 elevator shaft is a control valve 36 for controlling the passage of pressure fluid to the door operating engines 32. I have discovered that this unit 36, which must be very accurately placed in relation to the tripping lever (52) 55 position, may be mounted on a guide rail in the shaft, whereby it may be readily adjusted in position, and whereby the units may be uniformly mounted irrespective of the local variations in the walls and landings of the 60 shaft. This mode of mounting and installation of the unit, which has never heretofore been accomplished, results in a great saving of time, and cost in the installation, and greatly facilitates repair work on the apparatus. The unit 36 is mounted by means 65 of any suitable form of bracket 198 to one of the guide rails in the shaft. I preferably attach the unit to a counterweight rail, although the unit may be satisfactorily mounted upon one of the elevator guide rails as is 70 shown in Figures 11 to 13 of the drawings, in the manner which will be hereinafter more fully explained.

The control valve 36 comprises a housing 200 in which is a piston 202 having a stem 75 204 slidably mounted in a bearing 206. Attached to the end of the piston head 202 so as to form a tight fitting member in the cylinder is a leather washer 208, which may be held or fastened to the lower face of the piston by means of a holding member or disk 210. The washer 208 is adjusted in position so as to be forced against the walls of the surrounding cylinder and thereby substantially prevent passage of operating 80 fluid from one side of the piston to the other in the cylinder. The construction of the valve 36 is very similar to the corresponding part of the apparatus shown in Figure 10, which has been described, and operates 85 in a similar manner. To the top of the valve unit is connected a pipe 212 which is connected with the exhaust pipe 40 as indicated more particularly in Figure 1 of the drawings. A pressure fluid supply pipe 214 is 90 connected to the valve unit in the manner indicated more particularly in Figure 8, this pipe being connected to the supply line 38, as shown in Figure 1. A third connection 216 is connected to a pipe 34 (see Figure 2) which leads to the elevator shaft door operator 32 which in turn is operatively connected to the toggle levers 28 operating the doors 16. The lever 56 is pivotally connected to the valve unit 36 by means of a 95 bolt or other equivalent means 218 permitting suitable movement of the lever. Connected to the lever 56, or integral therewith, is an arm 220 which extends under the unit 36, and by a suitable connecting means 100 controls the operation of the valve unit. In order to limit the outward movement of the lever 56, a guide member 222 is connected to the unit preferably extending downwardly 105 on each side of the lever 56, as shown more particularly in Figure 6, and an engaging member or stop 224 is attached to the end of the lever so as to engage the guide member when the lever is swung outwardly, or in a clockwise direction about its pivot 110. 115 In order to normally maintain the lever 56 in the position in which the stop 224 engages the guide member 222, a spring 226 is mounted in contact with the arm 220 so as to exert a downward force thereon, thereby holding the lever in this position, corresponding to the closed position of the elevator doors. When the roller 54 comes in contact with the lever, however, so as to 120 displace the lever from its normal position, 125

the valve will be operated so as to supply pressure fluid to the elevator door operator 32. Mounted in the arm 220 preferably at the inner end thereof is a spring pressed stop or member 228, which is slidably mounted in a sleeve 230, and which serves as a yieldable lifting means for the controlling valve 248. The sleeve 230 is preferably held in position by means of a screw threaded cylindrical member 232, in which a spring 234 is mounted so as to maintain the stop member 228 normally in its raised position. In order to limit the upward movement of the stop 228 a pin 236 may be employed in connection with the stem 238 of the member 228, the pin passing through the stem externally to the cylinder or casing 232. In the lower end of the valve unit 36 is an opening or chamber 240 which is connected by means of a passageway 242 to a chamber 244 in the central portion of the valve housing. At the base of the chamber 240 and positioned so as to form one wall thereof is a valve housing 246 which is preferably connected and held in place by a screw threaded connection. In the valve housing is a valve 248, adapted to seat on a valve seat 250 and thus to cut off communication between the chamber 240 and the atmosphere, by closing the opening or port 252 around the valve stem 254 of the valve. Communicating between the cylinder chamber 256 in the housing and chamber 240 are passages 258, 260 serving to permit exhaust of pressure fluid from the chamber 256 through chamber 240 and through port 252 to the atmosphere when the valve 248 is raised from its seat 250. The construction of the valve unit 36 is very similar to the corresponding valve in the electro pneumatic unit 48, the passageways and ports in the valve being substantially similarly arranged.

The operation of the valve unit 36 when the elevator car is stopped in the shaft sufficiently near a landing so that the tripping lever roller may engage the valve operating lever is as follows: When the tripping lever 52 is swung with its roller 54 so that the roller engages the valve operating lever 56, this lever is swung inwardly until the roller 54 contacts with the guide members 222, thus preventing further inward movement of the lever. Through this movement the arm 220 is swung upwardly against the force of the spring 226, and the stop 228 contacts with the valve stem 254, raising the valve 248 from its seat and forcing a ball valve 262 upwardly against its seat in the passageway 242, thereby cutting off communication between the chamber 240 and the chamber 244 above the piston 202. As soon as the valve 248 is raised the pressure fluid in the chamber 256 below the piston 202 exhausts through passages 258 and 260

into the chamber 240, and from thence through the port 252, around the valve stem 254, into the atmosphere. As a consequence of the reduction in pressure in the chamber 256, the downward pressure of compressed air or other fluid on the other side of the piston 202 forces the piston downwardly, whereby communication between the central chamber 270 and the exhaust chamber 264 is cut off by means of a disk valve 272 which moves to its seat 274. With the downward movement of the piston 202 a disk valve 266, attached to the stem 204 on the opposite side of the chamber 270 from the disk valve 272, moves away from its seat 268, whereby communication between the chamber 244 and the inner chamber 270 is attained. In this position of the valve, fluid pressure from the supply pipe 38 passes through the connection 214 (see Figure 3) into the chamber 244 and around the seat 268 into the inner chamber 270, and from thence through the connection 216 and pipe 34 (see Figure 1) to the engine or operator 32, which through the toggle levers 28 opens the doors 16. When it is desired to close the elevator doors 16 the solenoid controlling switch in the controller handle 68, or the mechanical control handle 72, is operated to move the plunger 70 so as to release the pressure on the stem of valve 98, whereby the mechanism 48 is operated to retract the lever 52 and roller 54 connected therewith, whereby the lever 56 is returned by means of the spring 226 to its normal position in which the stop 228 is in contact with the guide member 222. Through this movement the stop member 228 releases the valve 248 which drops against its seat 250 cutting off communication between the chamber 240 and the atmosphere, and simultaneously with this action the ball valve 262 moves away from its seat and permits passage of pressure fluid from the chamber 244, in communication with the supply line 38, through the passageway 242 into the chamber 240. From the chamber 240 the pressure fluid passes through passageways 258 and 260 into the chamber 256 below the piston 202 which is then in substantially free communication with the supply pressure, whereby the piston 202 will be forced upwardly until the disk or valve member 266 moves against its seat 268 thereby closing communication between the chamber 244 and the inner chamber 270, which is in direct communication with the floor door operator 32. With the upward movement of the valve 202, not only is the passage of pressure fluid to the operator 32 cut off, but communication of the operator 32 with the exhaust line 40 is set up through the valve, which is accomplished by the movement of the disk valve 272 which moves away from its seat 274, whereby communication between the pipe 216 through the

central chamber 270 and exhaust chamber 264 takes place. As soon as the fluid pressure is released from behind the piston in the operator 32, the spring therein, which 5 has been compressed through the opening movement, serves to return the doors 16 to their closed position through the force applied to the toggle levers 28.

As soon as the controller 66 is operated by 10 moving the handle 68 to close the circuit through the elevator controlling circuit, the switches connected with the solenoids can no longer be closed, and the car gate cannot thereafter be opened until the controller 15 handle is again brought into the neutral position in which the car is stopped in the shaft. As soon as the elevator car moves away from the landing, the tripping lever 52 attached to the unit 48 under the car moves 20 out of the zone in which it can contact with the valve lever 56, and the shaft doors cannot thereafter be opened, except by hand operation from within the shaft, until the car is again brought to within the required 25 distance of the floor landing.

It is to be understood that various changes and modifications may be made in the device above described without departing from the spirit or scope of the invention as defined 30 in the claims. It is to be understood that by the term "guide rail", as employed in the claims I mean either an elevator guide rail or a counterweight guide rail.

The improvements herein described are 35 designed more particularly for use in connection with elevators or elevator door and car gate operation but it is to be understood that various features or improvements herein claimed are adapted to be employed in 40 other connections apart from elevator operation and are not therefore limited as to their use or application. The mechanism herein described might be employed, for example, where two elements are to be simultaneously operated when a predetermined position of another moving element is reached. It might be employed for example, in connection with the operation of rail-way signals where two signals are to be 45 automatically operated substantially simultaneously when a train or car reaches a certain position on the tracks. It is to be understood therefore, that the herein described embodiment of the invention constitutes only the preferred form thereof, and the scope 50 of the invention is not limited to the preferred embodiment of the invention, except as defined in the claims.

What is claimed as new is:

60 1. In an elevator door control system, an elevator shaft, an elevator car in said shaft, a guide rail in said shaft, doors in the said shaft located at various landings thereof, a plurality of motor-mechanisms operatively connected to said doors, means mount-

ed on said guide rail for controlling the operation of said motor-mechanisms, and means connected with said car for operating the last named means when the elevator car is within a predetermined distance of 70 the desired landing.

2. In an elevator door control system, an elevator shaft, an elevator car in said shaft, a guide rail in said shaft, doors in the said shaft located at various landings thereof, 75 a plurality of motor-mechanisms operatively connected to said doors, means adjustably mounted on said guide rail for controlling the operation of said motor-mechanisms, and tripping means operable from within 80 said car for operating the last named means when the elevator car is within a predetermined distance of the desired landing.

3. In an elevator door control system, an elevator shaft, a guide rail in the said 85 shaft, an elevator car in said shaft, a car gate on said car, a motor-mechanism operatively connected to said car gate, doors in the said shaft located at various landings thereof, a plurality of motor-mechanisms 90 operatively connected to said doors, means adjustably mounted on said guide rail for controlling the operation of the said motor-mechanisms, means for controlling the operation of said motor-mechanisms, means operatively connected to the last named means for causing operation of the said means mounted on the guide rail when the elevator car is within a predetermined distance of a 95 landing.

4. In an elevator door control system, an elevator shaft, an elevator car in said shaft, a guide rail in said shaft, doors in the said shaft located at various landings thereof, 100 a plurality of fluid pressure operated mechanisms connected to the said doors, control valves adjustably mounted on said guide rail for controlling the operation of said mechanisms, and means operable from within said car for operating said control valves when the elevator car is within a predetermined distance of the desired landing.

5. In an elevator door control system, an elevator shaft, a guide rail in the said shaft, an elevator car in said shaft, doors in the said shaft located at various landings thereof, 115 a plurality of fluid pressure operated mechanisms operatively connected to said doors, control valves mounted on said guide rail for controlling the operation of said mechanisms, and fluid pressure operated tripping means connected with said car and operable from within said car for operating the control valve at the desired landing when the elevator car is within a predetermined distance thereof.

6. In an elevator door control system, an elevator shaft, an elevator car in the said shaft, a guide rail in said shaft, doors in 130

- the said shaft located at various landings thereof, a plurality of pneumatically operated mechanisms operatively connected to the said doors, control valves adjustably mounted on said guide rail for separately controlling the operation of said mechanisms, a pneumatic engine on said car, a tripping lever operatively connected to said engine, means accessible within said car for operating said engine, and cams for operating said control valves adapted to be operated by said tripping lever when the elevator car is within a predetermined distance of the desired landing.
7. In an elevator door control system for the simultaneous operation of an elevator shaft door and car gate, a motor mechanism operatively connected to the shaft door, operating means mounted on a guide rail in the shaft for controlling the said motor mechanism, an electro pneumatic valve mounted on the elevator car and operatively connected to the car gate, means dependently operating with the said electro pneumatic valve for operating the operating means on the guide rail only when the elevator car is within a predetermined distance of the floor landing, and means for preventing operation of said electro pneumatic valve while the elevator car is in motion.
8. In an elevator door control system, an elevator shaft, an elevator car in said shaft, a guide rail in said shaft, doors in the said shaft located at various landings thereof, power means for operating the said doors, adjustable means mounted on said guide rail for controlling the operation of the said doors from said power means, and means connected with said car for operating the said adjustable means when the elevator car is within a predetermined distance of the desired landing.

Signed at New York city, N. Y. this 18th day of May, 1925.

HAROLD W. SHONNARD.
